ENGRAVING MACHINE

Reb B. Dodson, Post, Tex.

Application June 23, 1953, Serial No. 363,503

4 Claims. (Cl. 33—24)

1

This invention relates to an engraving machine.

The object of the invention is to provide an engraving machine which will facilitate the engraving of such articles as articles of jewelry including cigarette lighters, identification bracelets, watches, cups and the like.

Another object of the invention is to provide an engraving machine which will enable persons to accurately and easily engrave various articles with a great saving in cost and effort.

A further object of the invention is to provide an engraving machine which is extremely simple and inexpensive to manufacture.

Other objects and advantages will be apparent during the course of the following description.

In the accompanying drawings, forming a part of this application, and in which like numerals are used to designate like parts throughout the same:

Figure 1 is a side elevational view of the engraving machine, constructed according to the present invention.

Figure 2 is a front elevational view of the engraving machine.

Figure 3 is a sectional view taken on the line 3—3 of Figure 2.

Figure 4 is a sectional view taken on the line 4—4 of Figure 2.

Figure 5 is a sectional view taken on the line 5—5 of Figure 4.

Figure 6 is a fragmentary plan view of the copy holder showing a letter mounted thereon.

Figure 7 is a sectional view taken on the line 7—7 of Figure 6.

Figure 8 is a sectional view taken on the line 8—8 of Figure 1.

Figure 9 is a sectional view taken on the line 9—9 of Figure 1.

Figure 10 is a sectional view taken on the line 10—10 of Figure 1.

Referring in detail to the drawings, the numeral 10 designates a horizontally disposed base or plate which may be supported on vertically disposed feet or legs 11, Figures 1 and 2. Extending upwardly from the base 10 is a pair of spaced parallel vertically disposed cylindrical posts 12, the posts 12 being secured to the base 10 by suitable screws 14. Extending between the tops of the posts 12 and secured thereto in any suitable manner is a curved copy holder 15. The copy holder 15 carries a strip 16 which may be made of a suitable resilient material such as rubber whereby the copy member 17 will not accidentally slip out of place during use of the

2

machine. The numeral 18 designates the name or design on the member 17 which is to be reproduced on the work piece, Figures 6 and 7, and the copy member 17 may be provided with a lip 19 for facilitating the manual placement or removal of the member from the copy holder 15.

Arranged below the copy holder 15 is a work supporting member 20, and the supporting member 20 includes a pair of upturned flanges 21 which each have an inwardly extending ear 22. The ears 22 and main portion of the work support 20 are provided with registering openings such as the openings 24, Figure 4, and the posts 12 slidably support the work holder 20. Set screws 23 extend through the vertical portions 21 and into engagement with the posts 12 for maintaining the work support 20 immobile in its various adjusted positions. A work piece is indicated by the numeral 25, and the work piece 25 may be clamped on the work support 20 by a vise or other mechanism. The work piece 25 may be a bracelet, watch, or any other article which is to be engraved. The openings in the horizontal ears 22 are indicated by the numeral 24, Figure 5, and the openings below the openings 24 are indicated by the numeral 26.

Secured to the lower surface of the base 10 is a body member 27, Figure 11, and the body member 27 is provided with a socket 29 for receiving a ball 31 mounted on the front end of an arm 30. Thus, the arm 30 can swing or pivot due to the ball and socket construction. The body member 27 may be secured in place below the base 10 by suitable screws or bolt and nut assemblies 28.

The rear end of the arm 30 is connected to the lower end of a rod 31 which extends vertically, and the upper end of the rod 31 is shaped to provide a horizontally disposed bar 34. The rear portion of the arm 30 extends through a guide member 32 which is connected to the base 10, and the guide member 32 also coacts with the feet 11 to help support the engraving machine. The guide member 32 is provided with a cut-out or opening 33 for the projection therethrough of the arm 30, Figure 8.

Carried by the front end of the bar 34 is a tracing member 35, Figure 1. The tracing member 35 is spring pressed, and there is provided a collar 36 which is secured to the front end of the bar 34. A head 37 is mounted on the upper end of the vertically adjustable tracing member 35, and the lower end of the tracing member is pointed as at 38 for engagement with the letters

or indentations 18 on the copy. A coil spring 39 is spaced below the bar 34.

Secured to the undersurface of the bar 34 is a hollow sleeve 40, and a standard 42 is slidably or adjustably mounted in the sleeve 40, there being a set screw 41 extending through the sleeve 40 and into engagement with the standard 42 for maintaining the standard 42 immobile in its adjusted positions. The lower end of the standard 42 is connected to a horizontally disposed leg 43 and the rear portion of the leg 43 is bifurcated as at 44 for engaging the rod 31, Figure 10. Mounted on the front end of the leg 43 is a stylus or engraving member 45 which is adapted to engage the work piece 25. The engraving tool 45 includes a coil spring 47 that normally maintains the engraving tool in its raised position, and a pointed end 46 is provided for engagement with the work piece. A knurled knob 48 is mounted on the upper end of the standard 42 for facilitating the raising and lowering thereof.

From the foregoing it is apparent that an engraving machine has been provided which will facilitate the engraving of various articles such as articles of jewelry. The machine of the present invention can be used for engraving curved articles without the necessity of resetting the article. Thus, such articles as cigarette lighters, identification bracelets, watches, cups and the like can be engraved. In use, the screws 23 are loosened and the holder 20 is lowered on the base 19. Then, the work to be engraved, which is indicated by the numeral 25, is clamped on the holder 20 and then the standard 42 is adjusted to effect the desired ratio between the tracing instrument 35 and the cutting instrument 45. To obtain the desired adjustment for the proper ratio, the screw 41 is loosened and the standard 42 is moved up or down to the proper place and then the screw 41 is tightened. Then the desired letters such as the letter D, indicated by the number 18 is snapped in the copy holder 15 and then the work holder 20 is raised so that the object 25 to be engraved is from $\frac{1}{8}$ of an inch to $\frac{1}{4}$ of an inch within the cutting point 46. Then, with one hand the user guides the tracing instrument 35 through the copy while the other hand is used to press down on the engraving instrument 45 in order to engrave the article.

The advantages of the present invention are that the engraving leg 43 is in direct line between the tracing guide 35 and the ball and socket joint 27 in order to give an exact copy on a reduced scale with no moving hinge joints. Furthermore, the work is easily accessible for adjustment and the engraving ratio is quickly and easily changed. Since the letters or designs snap in the holder 20 separately, they can be placed side by side or spaced as desired. This is especially advantageous when initials are being placed on an article. The machine of the present invention is also simple and easy to manufacture and easy to operate and engraves all shapes and types of articles.

I claim:

1. An engraving machine comprising a horizontally disposed base, a plurality of vertically disposed legs supporting said base, a pair of spaced parallel posts extending upwardly from said base and secured thereto, a curved copy holder extending between the tops of said posts and secured thereto, said copy holder including a resilient strip for frictionally engaging the copy, a horizontally disposed work supporting member adjustably connected to said posts, a body member mounted below said base and provided with a socket, an arm having a ball on its front end rotatably seated in said socket, a guide member connected to the lower portion of said base for receiving the rear end of said arm, a vertically disposed rod extending upwardly from the rear end of said arm, and secured thereto, said rod including a horizontally disposed bar, a spring pressed tracing member connected to the front end of said bar, a sleeve secured to the undersurface of said bar, a vertically disposed standard adjustably mounted in said sleeve, a horizontally disposed leg connected to the lower end of said standard, and a spring pressed engraving member carried by the front end of said leg.

2. The apparatus as described in claim 1, and further including means for maintaining said work holder immobile in its adjusted positions.

3. The apparatus as described in claim 1, and further including means for maintaining said standard immobile in its adjusted positions.

4. An engraving machine comprising a base, a plurality of legs supporting said base, a pair of posts extending upwardly from said base and secured thereto, a copy holder extending between the tops of said posts and secured thereto, said copy holder including a resilient strip for frictionally engaging the copy, a work supporting member adjustably connected to said posts, a body member mounted below said base and provided with a socket, an arm having a ball on its front end rotatably seated in said socket, a guide member connected to the lower portion of said base for receiving the rear end of said arm, a rod extending upwardly from the rear end of said arm, and secured thereto, said rod including a bar, a spring pressed tracing member connected to the front end of said bar, a sleeve secured to the undersurface of said bar, a standard adjustably mounted in said sleeve, a leg connected to the lower end of said standard, and a spring pressed engraving member carried by the front end of said leg.
